UNITED STATES PATENT OFFICE

2,266,140

CHAIN-STITCH SEWING MACHINE

Frederick F. Zeier, Fairfield, Conn., assignor to
The Singer Manufacturing Company, Elizabeth, N. J., a corporation of New Jersey

Application April 15, 1939, Serial No. 267,958

28 Claims. (Cl. 112—199)

This invention relates to sewing machines, more particularly of the chain-stitch straight-away-feed type designed for accommodating comparatively heavy materials, and has for an object to provide an organized sewing machine of the type in question having improved characteristics enabling it to be commercially operated at speeds considerably in excess of those of previous machines of this type, without undue wear and tear on the various parts.

A second object of the invention is to provide an improved and novel looper operating mechanism, wherein the looper is given a variable motion such that it will cooperate with a needle having work-feeding movements regardless of the amplitude of these movements.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Referring to the drawings, Fig. 1 is a longitudinal vertical section through the frame of a machine embodying the invention, showing the internal mechanism.

Fig. 2 is a rear side elevation of the sewing machine with the oil drip-pan removed.

Fig. 3 is a front end elevation with the bed and work-supporting plate in section.

Fig. 4 represents a vertical section taken substantially along the line 4—4, Fig. 1.

Fig. 5 represents a horizontal section taken substantially along the line 5—5, Fig. 3.

Fig. 6 is a detail view in elevation of the feed-frame in which is journaled the reciprocating needle-bar.

Figs. 7 and 8 are enlarged fragmentary views of the thread-loop seizing end of the spreader-blade disclosed in Fig. 3 in position adjacent to and above the looper.

Fig. 9 is a top plan of the machine-bed with the bracket-arm and work-supporting plate removed therefrom to expose the mechanism within the bed.

Fig. 10 is an enlarged vertical section taken substantially along the line 10—10, Fig. 9.

Fig. 11 is an enlarged vertical section taken substantially along the line 11—11, Fig. 9.

Fig. 12 is a top plan of the bracket-arm of the machine with the head end in section, and illustrating the internal mechanism.

Fig. 13 is a horizontal section through the head of the machine taken substantially along the line 13—13, Fig. 3.

Fig. 14 is a vertical section taken substantially along the line 14—14, Fig. 1, showing the oil-metering device which is adapted to govern the amount of lubricant directed to the needle-bar crank and link.

Fig. 15 is an enlarged fragmentary perspective view of the lower portion of the oil-metering stem disclosed in Fig. 14.

Fig. 16 is an enlarged horizontal section taken along the line 16—16, Fig. 14.

Fig. 17 is a rear end elevation of the machine with the balance-wheel removed.

Fig. 18 is an end elevation of the counter-balance needle-bar crank showing clearly the eccentricity of the undercut recess formed therein.

Fig. 19 is a fragmentary front side elevation of a portion of the bracket-arm and head, showing the needle-thread controlling devices.

Fig. 20 is an enlarged vertical section taken substantially along the line 20—20, Fig. 9.

Fig. 21 is an enlarged vertical section taken substantially along the line 21—21, Fig. 9.

Fig. 22 is an enlarged vertical section taken substantially along the line 22—22, Fig. 9.

Fig. 23 is an enlarged vertical section taken substantially along the line 23—23, Fig. 9.

Fig. 24 is a top plan of the machine-bed with the work-supporting plate removed to expose the lubricant-distribution system.

Fig. 25 is a front side elevation of the machine-bed partly in section.

Fig. 26 is a top plan of the work-supporting plate secured upon the machine-bed.

Fig. 27 is a front side elevation of the machine-bed and work-supporting plate.

Fig. 28 is a front side elevation of the drip-pan which is adapted to enclose the machine-bed.

Fig. 29 is an enlarged vertical section taken substantially along the line 29—29, Fig. 26.

Fig. 30 is a front end elevation of the looper mechanism showing the paths of travel of certain of its elements, together with the corresponding path of travel of the point of the needle.

Fig. 31 is a front end elevation of the lower four-motion feeding mechanism showing the paths of travel of certain of its elements, together with the corresponding path of travel of the point of the needle.

Fig. 32 is a disassembled perspective view of the looper-mechanism and its actuating crank.

Fig. 33 is a graph showing two curves representing displacement, or velocity, of the looper and needle, together with a curve illustrating the velocity of a point traveling in simple harmonic motion.

The detailed description which follows is broken down into sections so as to facilitate a quick understanding of the various mechanisms of the machine and their operations. It should be understood that the present invention is not limited to the details of construction and arrangement of parts illustrated in the accompanying drawings for it is capable of other embodiments which come within the scope of the appended claims.

Frame and general structure

The frame of the machine illustrated forms the subject of a divisional application Serial No. 362,907, filed October 26, 1940.

The hollow frame, which is preferably cast in two pieces, comprises a rectangular bed 1 from one end of which rises a standard 2 of an overhanging bracket-arm 3 terminating in a head 4.

The rectangular bed 1 is composed of vertically disposed front and rear side walls 5 and 6, and end walls 7 and 8. Intermediate the end walls 7 and 8 are two dividing walls 9 and 10 which separate the bed 1 into three rectangular compartments 11, 12 and 13. Disposed in compartments 11 and 12 are the stitch-forming mechanism and the feeding mechanism, together with connections for actuating the same. Each of these two compartments is open at the bottom to permit the precipitation of spent oil, lint and dirt from the mechanism within these compartments. By reference to Fig. 1, it will be seen that compartment 13 forms the lower portion or sump of a lubricant chamber and is closed at the bottom by means of a removable circular sheet-metal cover-plate 14.

Secured upon the rear end-portion of the bed 1 is the standard 2 of the bracket-arm 3. The standard has integrally formed therewith a vertical internal partition 15 which extends from the rear end wall 8 of the bed 1 to a cover-plate 16 secured upon the top of the bracket-arm 3, and divides the space within the standard into the oil or splash-lubrication chamber 13 and a belt compartment 17. The open face of the standard is closed by means of a sheet-metal plate 18 which is adapted to protect the operator from contacting the driving belt housed within the belt compartment 17. In order to facilitate removal of the plate 18, it is provided with two keyhole-slots 19 entered by the spacing studs 20 threaded into the partition 15, and with a finger-hole 21, whereby the plate 18 may be easily grasped.

The bracket-arm 3 at the standard end is provided with an internal partition 22 and at its head end is provided with an internal partition 23, which partitions define a compartment housing the eccentrics and some of the connections for actuating the needle and top feeding mechanisms. In addition, partitions 22 and 23 provide bearing lugs for the ball-bearing 24 and the bearing bushing 25 in which is journaled the main or arm-shaft 26. To lend support to the end-portion of the arm-shaft 26 adjacent the standard 2, there is provided an additional ball-bearing 27, and supporting means therefor which is mounted in the vertical internal partition 15 of the standard 2. The supporting means for the ball-bearing 27 comprises a bushing 28 fixed in the partition 15 by the set-screw 29 and having

an axial bore 30, the diameter of which is slightly in excess of the diameter of the arm-shaft 26. The bushing 28 is formed at one end with a reduced end-portion 31 upon which is press-fitted the inner race 32 of a commercial ball-bearing 33. Press-fitted upon the outer race of the ball-bearing 33 is a belt-sprocket 34 of which the hub 35 is secured by set-screw 36 upon the arm-shaft 26. Fixed upon the end of the arm-shaft 26 is the usual belt-driven balance-wheel 37. With the ball-bearing supporting means above described, it will be obvious that the bushing 28, ball-bearing 33 and belt-sprocket 34 may be assembled as a unit and conveniently applied to the machine by merely tightening the set-screws 29 and 36.

Longitudinally of the bed 1 there is journaled in the bushing 38, ball-bearing 39 and ball-bearing 40, the lower rotary main-shaft 41 having secured upon one end thereof a belt-sprocket 42 of the same diameter as the belt-sprocket 34. These two belt-sprockets 34 and 42 are connected by means of a conventional clip-belt 43 to rotate at a ratio of one-to-one. It will be seen from Fig. 1 that the belt-sprocket 42, as in the case of belt-sprocket 34, in effect acts as a support for the end of the lower main-shaft 41 through the medium of the ball-bearing and the stationary bushing 44 secured in the wall 8 of the bed 1. The main-shaft 41 at its forward end-portion has secured thereto eccentrics and a crank for actuating the mechanism located within the bed 1.

Referring now to Figs. 26 to 29, inclusive, it will be observed that the bed 1 is provided with a work-supporting plate 45 detachably secured by means of four screws 46. In order that access may be had to the mechanism beneath the work-supporting plate 45, and to facilitate threading the looper, the work-supporting plate 45 is fitted with a removable cover-plate 47 held in position by the latch 48. This latch 48 yieldingly maintains the two corners 49 of the cover-plate 47 seated in undercut recesses formed in the work-supporting plate 45. The latch 48 is maintained in engagement with the cover-plate 47 by a bowed spring 50 the ends of which bear against a retaining strap 51 fastened beneath the work-supporting plate 45 by the screws 52. Endwise movement of the latch 48 is controlled by the stop-pin 53 of which the head enters an enlarged aperture 54 in the latch 48. Chatter of the cover-plate 47 is minimized in the present case by using only three point contact between the cover-plate 47 and the work-supporting plate 45, aided by the use of a strip of rubber or felt 55 on the latch 48. To facilitate removal of the cover-plate 47, the latter is formed with two finger-holes 56. In removing the cover-plate 47, the operator inserts a finger in each of the holes 56 and shifts the plate 47 to the right, Fig. 29, thereby disengaging the two corners 49 of the cover-plate from their respective recesses and permitting the same to be tilted and removed.

The machine bed 1 is adapted to be placed in an open-topped box-like drip-pan 57 having secured around its upper edge an L-shaped gasket 58 which prevents metal-to-metal contact between the machine-bed 1 and the drip-pan 57. It will be understood that the surplus oil supplied to the various bearings through piping later to be described, is collected in the drip-pan which periodically is drained through the plug 59 and cleaned out. The gasket 58 not only prevents the egress of oil from the drip-pan 57, but also functions as a vibration dampening expedient.

From the above description, it will be understood that a machine frame is provided in which all the mechanism housed thereby is conveniently accessible for assembly and repair by simply removing various plates. Particular notice is called to the machine-bed which consists of a skeleton frame having a removable work-supporting plate and a removable drip-pan. This construction is particularly advantageous in assembling and adjusting the machine, since it exposes all the mechanism within the bed.

Needle-bar mechanism

Formed upon the free end of the bracket-arm 3 is the usual head 4 which is of substantially conventional form. Pivotedly hung preferably upon a stud 60 secured by screws 61 in the top of the head 4 is a vibratory frame 62 formed with two spaced lugs 63 in which is journaled, for endwise reciprocation, a needle-bar 64 carrying at its lower end a needle 65. The lower end of the vibratory frame 62 is steadied in its movement by an L-shaped bracket 62' which is secured to the machine-head 4. Clamped upon the needle-bar 64 intermediate the lugs 63 is the usual split collar 66 having a hollow pin 67 connected by a tubular link 68 to a hollow crank-pin 69 carried by a counterbalanced crank 70 secured upon the end of the arm-shaft 26. A unique and novel oiling system has been devised for lubricating the needle-bar mechanism, and this system will be described in detail under the appropriate section of lubrication.

To assist in feeding the work through the machine, the needle is adapted to vibrate in the line of feed in timed relation with the various feeding elements. The vibratory movement of the needle is derived from an adjustable eccentric 71 mounted upon the arm-shaft 26 through connections clearly disclosed in Figs. 1, 2 and 3. Embracing the eccentric 71 is a short rearwardly extending pitman 72, the end of which is connected to the upper end of a vertically disposed lever 73 clamped at its lower end upon the end of a rock-shaft 74 journaled in spaced lugs 75 of the rear wall of the head 4. Pinned upon the other end of the rock-shaft 74 is the upper end of the depending lever 76 connected at its lower end by a horizontal link 77 to a split projection 78, see Fig. 6, formed upon the frame 62.

To provide for changing the amplitude of vibration of the needle, i. e., to change the length of stitch, provision must be made to permit adjustment of the amount of movement imparted to the needle. In the present case, the eccentric is constructed so that its eccentricity may be conveniently adjusted to give the desired stitch-length. The constructive features of the adjustable eccentric 71 used in the machine chosen for illustration need not herein be described, since the eccentric is disclosed and claimed in the United States patent to W. Myers, No. 2,128,031, issued Aug. 23, 1938. To assist in effecting adjustment of the eccentric 71, there is provided in the top of the bracket-arm 3 a detent 79 which is adapted to be depressed by the operator and to enter a suitable stop-notch in the adjusting member of the eccentric 71, permitting the operator to turn the balance-wheel 37 and adjust the eccentricity of the eccentric. The structural details of the detent 79 will not be described in detail, since it is disclosed in the United States patent to W. Myers, No. 2,063,264, dated Dec. 8, 1936, but its operation in connection with the present arrangement will be more fully described later in

this specification in connection with the lower four-motion feeding mechanism.

As described above, it will be understood that as the arm-shaft is rotated the needle-bar 64 is reciprocated endwise and at the same time is vibrated in the line of feed by the eccentric 71 and the connections actuated thereby.

Top-feeding mechanism

Assisting the needle in advancing the work through the machine, is a top four-motion feeding mechanism which is designed to cooperate with the presser-mechanism. This feeding mechanism, which forms the subject of a divisional application Serial No. 332,441, filed Apr. 30, 1940, comprises a feed-dog 80 carried in the usual way upon the lower end of a feed-bar 81 slidable in a vertical dovetailed guideway 82 formed in the vibratory frame 62. Referring to Figs. 5 and 6, it will be observed that in order to take up wear, and also to facilitate manufacture, one side of the dovetailed guideway 82 is in the form of a detachable gib 83 secured by screws 84 threaded into the vibratory frame 62.

Disposed adjacent the feed-dog 80 is a presser-foot 85 attached to the lower end of an endwise movable presser-bar 86 journaled in a fixed bushing in the head 4 of the machine. Clamped upon the upper end of the presser-bar 86 is a horizontal guide-arm 87, Fig. 13, the free end of which is adapted to enter the usual presser-bar guide-slot 88 provided in the rear wall of the machine-head 4. This guide-slot 88, in the present case, is preferably formed of two parallel hardened steel runners 89 and 90 secured one upon the outside of the wall of the machine-head 4 and the other upon the inside of the wall of the machine-head by screws 91 and 92.

Positioned directly above the upper ends of the feed-bar 81 and presser-bar 86 is an inverted T-shaped angle-lever 93 provided at the junction of the limbs thereof with a horizontally disposed fulcrum-pin 94 which is journaled in the end of the arm 95 freely fulcrumed upon the rock-shaft 74 adjacent the lever 76. The ends of the substantially horizontal limb of the angle-lever 93 are provided with pivot-pins 96 and 97. Pin 96 is connected by a depending link 98 to the upper end of the feed-bar 81, and pin 97 is connected by a depending link 99 to a lifting pin 100 carried by the presser-bar guide-arm 87. The upstanding limb of the angle-lever 93 is connected by the curved link 101 to the slotted rock-lever 102 pinned upon one end of a feed-advance rock-shaft 103 journaled in a lug 104 integral with the rear wall of the machine-head 4. Clamped upon the other end of the feed-advance rock-shaft 103 is the upstanding rock-lever 105, the upper end of which is connected by a pitman 106 actuated by an eccentric 107 secured upon the arm-shaft 26.

Referring now to Figs. 3 and 12, it will be seen that the free end of the arm 95 provides a floating fulcrum for the angle-lever 93. The arm 95 and the mechanism connected thereto are depressed preferably by a leaf-spring 108, the free end of which is concaved and engages the semi-spherical head of the screw 109 carried by the arm 95. The other end of the leaf-spring 108 is apertured to receive the retaining pin 110 of the lug 111, and intermediate the ends of the spring 108 there is provided an adjusting screw 112 for regulating the amount of pressure applied by the spring. It will be readily understood that the purpose of the leaf-spring 108 is to maintain either the presser-

foot 85 or the feed-dog 80 in engagement with the work upon the work-supporting plate 45.

Considering the top feeding mechanism in the position illustrated in Fig. 3, the operation thereof is as follows: Rotation of the arm-shaft 26 imparts to the angle-lever 93, through the eccentric 107 and connections actuated thereby, a constant oscillatory motion about the axis of the fulcrum-pin 94. When the presser-foot 85 engages the work, or the throat-plate as shown in Fig. 3, and the rock-lever 102 moves in a clockwise direction about the axis of the feed-advance rock-shaft 103, the pin 97 of the angle-lever 93 becomes the pivot-point about which the angle-lever turns. Further movement of the rock-lever 102 in the same direction raises the feed-bar 81 through the link 98 and also elevates to a small extent the spring-biased end of the arm 95. When the feed-dog 80 carried by the feed-bar 81 is thus lifted from the work, the vibratory frame 62, which carries the needle-bar 64 and the feed-bar 81, is shifted to the right through the vibration of the lever 76, Fig. 3, or, in other words, given its feed-return movement. At the end of this feed-return movement, the oscillation of the rock-lever 102 in a counterclockwise direction causes a turning of the angle-lever 93 about the pivot-pin 94 in a clockwise direction, which results in a lowering of the feed-dog 80 into contact with the work, in which position the pin 96 carried by the angle-lever 93 becomes the pivot-point about which the angle-lever turns. Further movement of the rock-lever 102 in the counterclockwise direction raises the presser-bar 86 through the link 99. When the presser-foot is thus raised from the work, the vibratory frame 62 carrying the needle-bar 64 and the feed-bar 81 has imparted to it, through its actuating connections previously described, the feed-advance movement. This sequence of operations above described is repeated in timed relation with a lower four-motion feeding mechanism which will later be described, and it will be understood that an improved work-feeding mechanism has been provided that will operate efficiently at high speeds.

In order that the amount of elevation of the presser-foot and feed-dog may be varied to compensate for materials of various thickness, the rock-lever 102 is slotted and has clamped thereto the curved link 101. Adjustment of the end of the link 101 in the slot 102' of the rock-lever 102 varies the amount of oscillation imparted to the angle-lever 93 which controls the height to which the presser-foot 85 and feed-dog 80 are raised.

It will be observed that the angle-lever 93 is connected by the two depending links 98 and 99 to the feed-bar 81 and presser-bar 86, respectively. The provision of these two links renders the top feeding mechanism exceedingly flexible and prevents any binding of the presser-bar or feed-bar in their respective guides. To facilitate assembly of the top feeding mechanism, the pivot-pins 96 and 97 as well as several others are held against axial displacement by conventional thin sheet-metal resilient retainers 113 which are seated in peripheral grooves formed in the end-portions of the pivot-pins.

From Figs. 1 and 3, it will be seen that in order to obtain a comparatively long stitch, the feed-bar 81 is spaced to the left of the vertical plane containing the longitudinal axes of the needle-bar 64 and the presser-bar 86, and also rearwardly of the needle-bar 64 so that the feed-bar 81 can move backwardly during the feed-stroke to a position substantially at the side of

the presser-bar 86. With the view of obtaining a more smoothly acting top feeding mechanism, and to minimize the endwise movement of the feed-bar 81 during the vibration of the frame 62, the axis of the stud 60 upon which the frame 62 is pivotally hung is in a plane which lies substantially midway between the longitudinal axes of the feed-bar 81 and the needle-bar 64, see Fig. 3.

10

Lower feeding mechanism

The lower four-motion feeding mechanism, which operates in synchronism with the needle-feed and top-feed mechanisms, comprises a feed-advance and -return rock-shaft 114 and a feed-lift rock-shaft 115 disposed on opposite sides of the lower main-shaft 41 journaled in the bed 1.

The feed-advance and -return rock-shaft 114 is journaled in two bushings 116 and 117 fixed in the walls 7 and 9, respectively, of the bed 1. Clamped upon the inner end of the rock-shaft 114 is a depending rock-lever 118, the lower end of which is connected by a pitman 119 to an adjustable eccentric 120 upon the lower main-shaft 41. The elements of the eccentric 120 are identical with the eccentric 71 on the upper main-shaft, and with the disclosure in the United States patent to W. Myers, No. 2,128,031, dated Aug. 23, 1938, previously referred to in the description of the needle-bar mechanism. Secured by screws 121 upon the outer end-portion of the rock-shaft 114 is the usual upstanding feed-rocker 122 carrying at its upper end a hollow fulcrum-bar 123 held against endwise movement by the cap-screws 124 threaded into the feed-rocker 122. Journaled upon the fulcrum-bar 123 is the bifurcated end of a feed-bar 125 formed with a guideway 126 entered by the shank of the lower feed-dog 127, the shank having threaded into it a clamp-screw 128 for securing the feed-dog 127 in vertically adjusted position. Formed in the feed-dog 127 is a needle-aperture 127' which is adapted to receive the needle 65 and back up the same during feeding of the work.

The feed-lift rock-shaft 115 is supported at its outer end by a pintle 129 fixed in the wall 7 of the bed 1, and at its inner end by a pintle 130 fixed in a lug 131 integral with the wall 6 of the bed 1, see Fig. 22. Depending from the inner end of the feed-lift rock-shaft 115 is a rock-lever 132, the lower end of which is connected by a short pitman 133 actuated by an eccentric 134 fastened upon the lower main-shaft 41. Extending horizontally and forwardly from the outer end of the feed-lift rock-shaft 115 is a rock-lever 135, the free end of which is connected by the depending links 136 to the free end of the feed-bar 125.

In a machine having an upper feeding mechanism and a lower feeding mechanism each deriving its work-advancing movements from independent adjustable eccentrics means must be provided to enable the two feeding mechanisms to remain in unison during the adjustment of the stitch-length. From Fig. 10, it will be observed that the adjusting element of the eccentric 120 is held stationary by means of a pivotally mounted detent 137 having an offset finger-plate 138 overlying the free end of a spring-wire 139 which normally maintains the detent 137 elevated into inoperative position. Access to the detent 137 may be had by removing the cover-plate 41 of the work-supporting plate 45. In adjusting the stitch-length of the upper and lower feeding mechanisms, the balance-wheel is manu-

75

ally turned until the detent 79 on the bracket-arm 3 registers with the stop notch in the eccentric 71 of the upper feeding mechanism, in which position the detent is depressed and turned, thereby locking the same in latching position. This leaves one hand of the operator free so that the detent 137 for the adjustable eccentric 120 upon the lower main-shaft 41 may be manually held in latching position while the balance-wheel is turned with the other hand of the operator until the required amount of eccentricity has been obtained. To resume sewing, the detent 137 is released, as is also the detent 79. It is obvious from the above description that efficient means have been provided whereby the separate eccentricities for the upper and lower feeds may be comitantly adjusted to vary the eccentricity thereof.

Fig. 31 shows the loci of travel of the various elements of the lower feeding mechanism, as well as that of the point of the needle. Particular attention is called to the comparatively flat upper half of the locus F, which is the path of travel of a point on the feed-dog 127. This comparatively flat portion of the locus F is the path of travel of a point on the feed-dog 127 above the throat-plate, and the advantages of such a flat path of travel of the feed-dog are appreciated by those skilled in the art.

An efficient lubricating system has been incorporated in the machine to oil the moving parts of the lower feeding mechanism, and this system will be described in detail later under the appropriate section of lubrication.

Looper mechanism

The looper-mechanism of the present machine is of the two-motion type and the looper is oscillated in a vertical plane parallel to the direction of feed about a fixed axis, the loop-seizing motion being in a direction opposite to the direction of the feed of the work through the machine. The looper-mechanism comprises a looper 140 of which the cylindrical shank 141 is secured in a carrier 142 fixedly clamped upon an oscillatable sleeve 143 journaled upon a tubular supporting rod 144 fixed in the bushings 145 and 146 in the walls 7 and 9, respectively of the bed 1. The oscillatable sleeve 143 is actuated from the lower main-shaft 41 through connections adapted to give the looper 140 a variable motion. These connections comprise a depending rock-lever 147 fastened by screws 148 upon one end of the oscillatable sleeve 143, one of the screws 148 engaging the flat 149 milled in the sleeve 143. Disposed in the lower end of the depending lever 147 is a hollow pin 150 upon which is journaled the lower end of a link 151. The upper end of the link 151 is journaled upon a hollow pin 152 fixed in the lower end of a second link 153 which is journaled at its upper end upon a hollow crank-pin 154 carried by a counterbalanced crank 155 fixed upon the outer end of the lower main-shaft 41. Freely fulcrumed upon the oscillatable sleeve 143 intermediate the depending rock-lever 147 and a securing split-ring 156 is a collar 157 provided with a substantially horizontal cylindrical guide-rod 158 slidably received in a suitable control-sleeve 159 formed in the link 153.

It will be observed from Fig. 30 that the looper-carrier 142 is directly connected to the counterbalanced crank 155 through connections 147, 151 and 153, and that the amount of movement imparted to the looper-carrier 142 is controlled by the cylindrical guide-rod 158 which maintains

and forces the link 153 into predetermined positions as the crank 155 is rotated. In other words, the effective leverage between the crank 155 and looper-carrier 142 is so varied that the looper 140 travels at a variable velocity, the instantaneous values of which are plotted in Fig. 33. In this figure, the ordinate represents displacement of the looper and needle, and the abscissa represents degrees of rotation of the main-shaft beginning at the lowermost point of the needle-bar stroke. By comparing the velocity curve of the looper with the velocity curve of a point traveling in simple harmonica motion, Fig. 33, it will be observed that the slope of the looper curve from the needle-loop shedding position to the needle-loop seizing position is relatively steep, indicating a very marked and rapid change in the speed of the looper. This change in speed of the looper of the present machine at this portion of the stitch-forming cycle is desirable and, in fact, necessary since, from Fig. 30, it will be seen that the looper and needle at the loop-shedding point are each moving in the same direction (direction of feed) and that before the eye of the needle rises above the point of the looper the latter must travel to the end of its loop-shedding stroke and then advance to loop-seizing position in a relatively short time. In Fig. 30, the locus A is the path of travel of the point of the needle at maximum stitch-length, while locus B is the path of travel of the point of the needle at minimum stitch-length.

From the above description considered in connection with Figs. 30, 32 and 33, it will be understood that a novel two-motion looper-mechanism is provided that will impart to the looper a variable motion of such a character as to render the looper-mechanism particularly applicable to a needle-feed machine.

Spreader mechanism

To assist in stitch-formation, the two-motion looper 140 has cooperating therewith a spreader 160 which is adapted to distend the looper-thread to form the usual triangle with the previous needle thread-loop for entrance by the descending needle. The spreader 160 at its free end is formed with two laterally spaced thread-engaging notches 161 and 162, see Figs. 6 and 7. During the normal operation of the machine, the looper-thread is engaged by the notch 161, but if, for any reason, during stitch-formation the thread should escape the notch 161 the same will be engaged by the notch 162. In other words, the second notch 162 is provided in the spreader 160 to insure proper stitch-formation.

The other end of the spreader is preferably slotted as at 163, see Fig. 9, and secured by a clamp-screw 164 upon one end of a reciprocatory supporting rod 165 journaled in a fixed bushing 166 in the wall 9 of the bed 1. Attached for endwise adjustment upon the other end of the supporting rod 165 is a head 167 (Fig. 10) connected by a link 168 to an upstanding rock-lever 169 formed integral with an oscillatable transverse sleeve 170. This sleeve 170 is preferably journaled upon a hollow rod 171 fixed at its opposite ends in lugs 172 and 173 formed upon the walls 5 and 6, respectively, of the bed 1; the sleeve 170 being held against endwise movement upon the hollow rod 171 by a collar 174. Formed integral with the sleeve 170 at the end remote from the rock-lever 169 is a second rock-lever 175 provided in its free end with a short rod 176 supporting a ball 177 adapted to be received in

a split socket 178 formed in the upper end of a relatively short pitman 179 actuated by an eccentric 180 secured upon the lower main-shaft 41, see Fig. 11.

The eccentric 180 is timed so that the spreader 160 is reciprocated crosswise of the line of seam formation at the proper time to spread the thread leading from the looper-eye to form the usual thread triangle with the previous needle-loop which is about the blade of the looper for proper entrance by the descending needle.

From the above description, it will be understood that the position of the spreader 160 with respect to the looper 140 and the needle 65 may be conveniently adjusted by virtue of the slotted end of the spreader 163 and the endwise shiftable head 167 secured upon the supporting rod 165.

Presser-foot lifting mechanism

The presser-foot 85 and the top feed-dog 80 are adapted to be raised either by the usual hand-controlled lifting lever or by knee or foot operated mechanism.

The preferred form of hand-controlled lifting lever is best illustrated in Figs. 2, 3, 12 and 13. It comprises a rearwardly extending lever 181 provided with a handle 182 at its free end, and at its other end is formed integral with or otherwise secured to a relatively long hub 183 of the lifting cam 184 journaled upon a stud-pin 185 projecting from the machine-head 4. As the lever 181 is raised, the lifting cam 184 is adapted to engage under the presser-bar guide-arm 87 which is clamped upon the presser-bar 86, thereby elevating the presser-foot from the work. The raising of the presser-bar guide-arm 87 transmits a lifting force through the link 99 and the angle-lever of the upper feeding mechanism to the free end of the arm 95, which causes the same to turn in a counterclockwise direction about the rock-shaft 74 in opposition to the leaf-spring 108. The turning of the arm 95 in a counterclockwise direction obviously elevates the top feed-bar 81 which is connected to the arm 95 through the link 98 and the angle-lever 93. From the above it will be understood that a raising of the lever 181 will elevate both the presser-foot 85 and the top feed-dog 80.

The presser-bar guide-arm 87, as previously described, is provided with a lifting pin 100, the inner end of which enters a vertically disposed clearance slot 186 formed in the lower end of a link 187 connected at its upper end to the horizontal arm 188 of a bell-crank lever pivoted upon a fulcrum-stud 189 projecting from the rear wall of the machine-head 4. Fastened upon the up-standing arm 190 which forms the other limb of the bell-crank lever is a comparatively long wire link 191 secured at its other end to an up-standing arm 192 formed with a hub 193 journaled upon a supporting pin 194 fixed in the rear wall of the standard 2. Formed upon the outer end of the hub 193 is an inclined block 195 channeled to receive either the foot-actuating lever 196, shown in full lines in Fig. 2, or the knee-actuated lever 197, shown in dotted lines in Fig. 2. The provision of a presser-lifter mechanism adapted to receive interchangeably either a foot-actuated lever or a knee-actuated lever is of course advantageous, since it enables the sewing machine to be set up as desired by individual operators.

The hand-controlled lifting lever 181 can be actuated independently of the knee- or foot-op-

erated mechanism for a major portion of its arc of movement by virtue of the clearance slot 186 formed in the link 187. It will be appreciated that a raising of the hand-controlled lever 181 results in a moving of the pin 100 from the lower end of the clearance slot 186 to the upper end of the clearance slot, without imparting any movement to the knee- or foot-operated mechanism until the pin engages the upper end of the clearance slot 186. In order to maintain the link 187 in its lowest position, the arm 190 of the bell-crank lever has bearing against it a spring 198 which is coiled about and secured to the fulcrum-stud 189 of the bell-crank lever.

In order that the needle-thread may be relieved of its tension when the presser-foot and top feeding foot are raised, the upper end of the up-standing arm 192 (Figs. 12 and 17) has fixed thereto a cam-arm 198' which when actuated by either the hand-lifting lever 181 or the knee- or foot-operated mechanism engages the end of the tension-releasing pin 199 and shifts the same endwise in opposition to the coil-spring 200. The endwise movement of the releasing pin 199 separates the tension-disks 201 of the usual tension device 202 supported upon a plate 203 secured upon the cover-plate 16.

Thread-handling mechanism

The mechanism of the present machine for controlling the needle-thread T^N is best shown in Fig. 19. The thread T^N traveling from the supply passes first through the intermittent tension 202, the nipper 204, take-up 205, thread-controller 206, auxiliary tension device 207, thread-guide 208 and finally to the eye of the needle 65. The intermittent tension 202 is of conventional design and is actuated as described in the previous section entitled "Presser-foot lifting mechanism."

The nipper 204, a cross-section of which is shown in Fig. 12, comprises a supporting pin 209 carrying at its outer end two opposed thread-disks 210 and at its inner end is formed with a head 211 straddling a roller 212. The roller 212 is normally held in contact with an actuating cam 213 on the arm-shaft 26 by a coil-spring 214 which acts between the head 211 of the pin 209 and an adjustable nut 215 threaded into a stationary sleeve 216 fixed in the bracket-arm 3. Mounted upon the outer end of the sleeve 216 is a U-shaped plate 217 prevented from turning by the screw 218 threaded into the bracket-arm 3. The limbs of the U-shaped plate 218 are each provided with a single thread-eye 219 for guiding the thread T^N . It will be understood that as the arm-shaft 26 is rotated, the actuating cam 213 fixed thereto intermittently moves the supporting pin 209 endwise, whereby the thread-disks 210 are separated and the thread T^N may be drawn therebetween.

From the nipper, the thread T^N is led to the take-up 205. This take-up comprises an arm 220 fastened directly upon the upper end of the needle-bar 64 by means of the screw 221 and having at its free end a thread-eye 222 through which passes the thread T^N . The thread-controller 206 comprises an arm 223 forming a continuation of the split collar 66 to which is connected the needle-bar link 68, the free end of the arm 223 projecting through a vertical slot 224 in a plate 225 secured upon the front wall of the machine-head 4. The arm 223 has secured upon the free end thereof a U-shaped member 226 having two thread-eyes 227. Intermediate the two limbs of the U-shaped member 226 is a thread-controlling arm 228 secured for adjust-

ment by a screw 229 upon the needle-bar link 68. The thread-controlling arm 228 is formed with a thread-slot 230 having a thread take-up portion 230', the thread T^N passing through the thread-slot in its travel from one of the thread-eyes 227 to the other thread-eye 221. It will be seen from Fig. 3 that the arm 223 supporting the thread-eyes 227 and the thread-controlling arm 228, as a result of the way in which each is supported, have a differential action relative to each other, which action effects a periodic take-up of the thread T^N . During the descending stroke of the needle 65 and prior to the penetration of the work by the needle, the thread-controlling arm 228 moves downward relative to the thread-eyes 227 in the member 226 and during this downward movement the take-up portion 230' retains possession of the thread and takes up slack thread between the thread-controller 206 and the eye of the needle 65. This take-up action is desirable so as to hold the thread T^N against the blade of the needle 65 in the vicinity of the eye thereof as the needle penetrates the work. During the upstroke of the needle 65, the thread-controlling arm 228 moves upwardly relative to the thread-eyes 227 and this relative upward movement is beneficial in that the resulting thread take-up action assists the needle in setting the previously formed stitch.

A thread pull-off 231 is secured upon the bracket-arm 3 and this pull-off 231 has an offset free end 232 over which the needle-thread T^N is laid as the take-up 205 reciprocates with the needle-bar 64. The effectiveness of this thread pull-off 231 may be regulated by simply loosening the clamping screw 233 and turning the pull-off about the pivot-screw 234, see Fig. 19. The function of the above described pull-off is to draw a short length of thread T^N from the supply so that the thread-loop cast out by the needle 65 at the beginning of its upstroke will be sufficiently large so that the beak of the looper 140 can unerringly enter the same.

The control of the looper-thread T^L from any suitable supply is accomplished as illustrated in Fig. 9. The looper-thread T^L is led through the guide-tube 235 to the split thread-eye 236 of the tension-device 237, then through the single disk rotary take-up 238, to the thread-guiding tube 239, thence to the looper 140. The single disk rotary take-up 238 is of conventional design and is substantially the same as the take-up disclosed in the United States patent to A. B. Clayton, No. 2,095,212, issued Oct. 5, 1937. It will be observed from Figs. 1, 9 and 22 that the plate 240 supporting the thread-guides of the rotary take-up 238 is mounted upon a bracket 241 which is rigidly secured upon the reduced, extended end 242 of the pintle 130 in the lug 131 of the bed 1. To facilitate placing the looper-thread T^L in the thread-guiding tube 239, the latter is formed with a helical slot 243, see Fig. 9, as are also the two freely rotatable sleeves 244 mounted upon the ends of tube 239. In placing the thread in the tube 239, the end sleeves 244 are turned until the slots therein are in register with the helical slot 243. The thread T^L is then laterally introduced into the tube 239 and the sleeves 244 turned in order to lock the thread in the tube.

From the above description it will be understood that only one needle-thread and one looper-thread are utilized in the formation of a single row of two-thread chain-stitches. Multiple rows of stitches may be made by simply using a plu-

rality of needle-threads and a plurality of looper-threads.

Lubrication

In order that the machine may be operated at high speed there is provided an automatic lubricating system which thoroughly oils all the bearing points in the machine. This lubricating system forms the subject of a divisional application Serial No. 339,438, filed June 8, 1940. In the bed 1 and standard 2 of the machine is an oil-chamber 13 having a sump closed at the bottom by means of a removable circular cover-plate 14, see Fig. 1. Oil is introduced into the chamber 13 through an oil-cup 245 threaded into the wall 10 of the bed, the level of the oil being determined by the top of the oil-cup 245. Contacting the oil contained in the chamber 13 is an oil-sling in the form of a ring 246 running on a grooved driving collar 247 secured upon the lower main-shaft 41. This oil-sling during the operation of the machine creates an oil-mist throughout the entire oil-chamber 13 of the machine and the oil suspended in this atmosphere is deposited upon an inclined collector plate 248 at the top of the chamber 13. The oil upon the collector plate 248 runs off the same and into an open-topped reservoir 249 sustained in position at the upper end of the chamber 13 by two retaining screws 250. Projecting into the reservoir 249 is a horizontal lubricant-conduit 251 which extends lengthwise of the bracket-arm 3 and terminates in the partition 23 adjacent the machine-head 4.

Mounted upon the conduit 251 adjacent the partition 23 is a block 252, see Fig. 4, held against endwise movement by screws 253 which bear against the conduit 251. Drilled lengthwise of the block 252 is a bore 254 connected to the conduit 251 by the duct 255. Disposed in the bore 254 are wicks 256, the ends of which project beyond the ends of the block 252 and wipe against the wicks 257 and 258 disposed in cavities formed in the pitmen 72 and 106, respectively, of the top feeding mechanism, see Fig. 12, thereby to distribute oil through the longitudinal bores 259 and 260 of the pitmen 72 and 106 to the pivot-points. It will be understood from the above that oil is conducted from the conduit 251 to some of the bearing points in the top feeding mechanism, and that the amount of oil delivered is effectively controlled by metering screws 261 in the block 252 which are adapted to compress and so vary the porosity of the wicks 256.

Referring now to Fig. 14, it will be seen that intersecting the conduit 251 in the partition 23 is a horizontal transverse bore 262 opening into a vertical bore 263 extending through the bearing bushing 25 in the partition 23 and opening into the arm-shaft bearing surface of the bushing 25. Adjacent the bottom of the vertical bore 263 in the bearing bushing 25, see Fig. 1, is a relatively small horizontal bore 264 terminating in a peripheral groove 265 formed in the reduced end-portion 266 of the bushing 25. The reduced end-portion 266 of the bushing 25 extends into an undercut recess 267 in the counterbalanced needle-bar crank 10 which recess, as shown in Fig. 18, is eccentrically located with respect to the axis of the arm-shaft 26. Extending radially from that portion of the undercut recess 267 which is at the greatest distance from the axis of rotation of the arm-shaft 26 is a bore 268 opening into the central bore 269 of the hollow crank-pin 69, which central bore 269 is connected by radial ducts to a central bore 270 of the hollow

needle-bar link 68. It will be understood that oil is conducted from the lubricant conduit 251, through the bores 262 and 263 to the bearing surface in the bushing 25, and that oil is also conducted from the vertical bore 263 through the bore 264 to the peripheral groove 265, where the oil drips off into the undercut recess 267 and by centrifugal force is caused to move along the inclined side of the recess 267 to the point which is at the greatest distance from the axis of rotation of the arm-shaft 26 where it enters the radial bore 268 and is finally distributed to the bearings at the opposite ends of the needle-bar link 68.

In order to effectively control the amount of lubricant to be conveyed to the bearing bushing 25 and the needle-bar mechanism, two metering devices 271 and 272 are used. The metering device 271, best shown in Figs. 14, 15 and 16, comprises a hollow stem having at its upper end a flange 273 maintained seta in a cavity 274 in the bracket-arm 3 by a lock-nut 275. At its lower end, the stem is provided with a head 276 having three vertical grooves 277, 278 and 279. Grooves 277 and 278 open into the bottom surface of the head 276 and permit the oil in the vertical bore 263 to drain into the shaft bearing in the bushing 25. Groove 279 is provided so that the oil contained in the vertical bore 263 may drain into the horizontal bore 264 in the bearing bushing 25. To vary the volume of oil delivered to the horizontal bore 264 it is only necessary to loosen the lock-nut 275, insert a screw-driver in the slot 280 in the top of the stem and turn the same to bring the groove 279 out of register more or less with the horizontal bore 264 in the bearing bushing 25. By thus varying the size of the opening between the head 276 of the metering device and the horizontal bore 264 more or less oil is delivered to the needle-bar mechanism. The stem of the metering device is made hollow and is provided with several radial ducts 281 so that the shaft bearing in the bushing 25 may be manually oiled after the machine has been at rest for a considerable period of time. The metering device 272 disclosed in Fig. 1 is preferably a screw-stud having an attenuated body 282 and an enlarged head 283 which fits snugly within the central bore 269 of the hollow crank-pin 69. It will be understood that by turning the screw-stud out of the central bore 269, the enlarged head 285 will move across the outer end of the bore 268 in the needle-bar crank 70 and thereby materially reduce the amount of oil delivered to the needle-bar crank-pin 69 and link 68.

In the event that the undercut recess 267 in the counterbalanced needle-bar crank 70 becomes flooded with oil, the excess is thrown off by the oil-sling 70' which is formed on the needle-bar crank 70 and returned within the bracket-arm 3 by the inclined drainage duct 284 in the bearing bushing 25. Any excess oil collected in the bracket-arm 3 is returned to the lubricant-chamber 13 through the drainage duct 285 in the partition 22.

Considering now the lubricating of the mechanisms beneath the work-supporting plate 45, it will be observed in Figs. 17, 24 and 25 that in the lower portion of the lubricant-chamber 13 there is provided an oil-collecting plate 286 having two troughs 287 and 288 formed therein. Trough 287 is provided with an aperture which overlies a reservoir 289, and trough 288 is provided with an aperture which overlies a reservoir 290. Each of these reservoirs is preferably split at one end and wedged in the end-wall 8 of the bed 1 by

a tapered screw 291. Secured to the other end of the reservoirs are lubricant-mains 292 and 293, one of which is fitted with a regulating screw 291' for controlling the amount of oil delivered thereby.

Projecting from the main 292 are oil-pipes 294, 295, 296 and 297, and projecting from the main 293 are oil-pipes 298, 299, 300, 301 and 302. Each of the oil-pipes projecting from the lubricant-mains is wick-filled and is adapted to distribute the oil by capillary attraction to the various wick-filled pockets and oil-holes in the connections and bearings in the mechanism within the bed.

Tracing the flow of oil from each oil-pipe, it will be seen from Figs. 22 and 24 that oil-pipe 294 delivers oil to an oil-hole in the lug 131 integral with the rear wall 6 of the bed 1 and that the oil is led from the oil-hole into a central bore 303 in the stationary pintle 130 and then into a central bore 304 in the feed-lift rock-shaft 115, lubricating the supporting bearings therefor. Oil-pipe 295, see Figs. 10 and 24, delivers oil to the oil-hole 305 in the supporting lug 172 for the hollow rod 171 upon which is journaled the sleeve 170. Oil-pipe 296, see Figs. 23 and 24, delivers oil to an oil-hole 306 in the wall 9 of the bed 1, the oil lubricating the bushing 117 through the duct 306' and ultimately finding its way through the duct 306'' along a central bore 307 in the rockshaft 114, lubricating all the bearings therefor, as well as other bearings for the feed-rocker 122 and feed-bar 125. Oil-pipe 297, see Figs. 20 and 24, conveys oil to an oil-hole 308 in the wall 9 of the bed 1, the oil-hole 308 terminating in the bearing surface of a bushing 38 in which is journaled the lower main-shaft 41. The surplus oil in this shaft bearing is collected at one end of the bushing 38 upon a reduced portion 310 thereof. This reduced portion 310 is received in an undercut 311 formed in the inner face of the looper-actuating crank 155 and the oil collected on the reduced portion 310 drips into the undercut 311 and is conveyed by a central bore 312 and radial ducts 313 in the crank-pin 154 to the sleeve 159 and the guide-rod 158. Surplus oil from the sleeve 159 and guide-rod 158 lubricates the hollow pin 152.

Oil-pipe 298, see Figs. 9, 11 and 25, delivers oil to a wick-filled pocket 314 in the pitman 133 which connects the feed-lift rock-shaft 115 with the eccentric 134 on the lower main-shaft 41. Oil in the wick-filled pocket 314 lubricates the eccentric 134 and the pivot-pin at the opposite end of the pitman 133. Oil-pipe 299, see Figs. 11, 24 and 25, delivers oil to a laterally projecting wick 315 carried by the pitman 133 which actuates the spreader mechanism. The wick 315 contacts the surface of the eccentric 180 and effectively lubricates the same. Oil-pipe 300, see Figs. 23, 24 and 25, delivers oil through an oil-hole 316 in the end-portion of the feed-advance and -return rock-shaft 114 into the central bore 307, thereby assisting in furnishing oil to lubricate most of the bearings for the lower feeding mechanism. Oil-pipe 301, see Figs. 10 and 24, conveys oil to a wick-filled pocket 317 formed in the pitman 119 which connects the feed-advance and -return rock-shaft 114 with the adjustable eccentric 120 on the lower main-shaft 41, the oil in the pocket 317 lubricating the adjustable eccentric and being conveyed by the longitudinal bore 318 to the opposite end of the pitman 119. Oil-pipe 302, see Figs. 21 and 24, delivers oil through an oil-hole 319 to a central bore 320 in the tu-

bular supporting rod 144, the oil in the central bore 320 being conducted by radial ducts 321 to a cut-out 322 in the sleeve 143 upon which is clamped the looper-carrier 142.

From the above description, it will be understood that an automatic lubricating system has been provided which, while the machine is in operation, thoroughly and effectively oils all the bearing points without attention by the operator, except of course when the machine has been idle for a considerable period of time in which case priming holes have been provided, whereby the operator may initially oil the machine. Obviously any surplus oil which is thrown off by the operating parts within compartments 11 and 12 in the bed 1, or collected on the operating parts when they are not in operation, is collected in the drip-pan 57 which may be periodically cleaned out.

To facilitate retaining the oil-sling ring 246 in operative position upon the driving collar 247, the oil-collecting plate 286 is preferably formed with a horizontally disposed retaining finger 322 (Fig. 17) which overlies the oil-sling ring 246 and prevents the same from becoming dislodged from the driving collar 247 during shipment of the machine.

The invention is not to be understood as limited to the specific embodiment thereof shown and described.

Having thus set forth the nature of the invention, what I claim herein is:

1. In a sewing machine the combination of an endwise reciprocatory needle-bar; a frame in which said needle-bar is journaled adapted to be vibrated in the line of feed; a needle carried by said needle-bar; complemental stitch-forming mechanism including a chain-stitch looper having loop-seizing and loop-shedding movements only cooperating with said needle; work-feeding mechanism including means for engaging the work upon opposite sides thereof; and means for operating said work-feeding mechanism in synchronism with the vibratory frame in which said needle-bar is journaled.

2. In a sewing machine the combination of an endwise reciprocatory needle-bar; a frame in which said needle-bar is journaled adapted to be vibrated in the line of feed; a needle carried by said needle-bar; complemental stitch-forming mechanism including a chain-stitch looper having loop-seizing and loop-shedding movements only cooperating with said needle; and work-feeding mechanism operated in synchronism with the vibratory frame in which said needle-bar is journaled; said feeding mechanism including a feed-dog provided with an aperture for receiving the needle, thereby permitting said feed-dog to back up said needle during the feeding of the work.

3. In a sewing machine the combination of an endwise reciprocatory needle-bar; a frame in which said needle-bar is journaled adapted to be vibrated in the line of feed; a needle carried by said needle-bar; a thread enchain looper cooperating with said needle in the formation of chain-stitches and confined to movement substantially in the line of feed; and work-feeding mechanism operated in synchronism with the vibratory frame in which said needle-bar is journaled; said feeding mechanism including a feed-dog provided with an aperture for receiving the needle, thereby permitting said feed-dog to back up said needle during the feeding of the work.

4. In a sewing machine the combination of an endwise reciprocatory needle-bar; a frame carrying said needle-bar and adapted to be vibrated in the line of feed; a needle secured to said needle-bar; complemental stitch-forming mechanism including a chain-stitch looper having loop-seizing and loop-shedding movements only cooperating with said needle; work-feeding mechanism including means for engaging the work upon opposite sides thereof; and means for operating said work-feeding mechanism in synchronism with the vibratory frame in which said needle-bar is carried.

5. In a sewing machine the combination of an endwise reciprocatory needle-bar; a frame carrying said needle-bar and adapted to be vibrated in the line of feed; a needle secured to said needle-bar; complemental stitch-forming mechanism including a two-motion chain-stitch looper cooperating with said needle and adapted to oscillate in a plane parallel to the line of feed; work-feeding mechanism including means for engaging the work upon opposite sides thereof, and means for operating said work-feeding mechanism in synchronism with the vibratory frame in which said needle-bar is carried.

6. In a sewing machine the combination of an endwise reciprocatory needle-bar; a frame carrying said needle-bar and adapted to be vibrated in the line of feed; a needle secured to said needle-bar; a thread enchain looper cooperating with said needle in the formation of stitches; a loop-spreader adapted to engage the looper-thread and position the same so that the needle will pass into the looper-thread loop; and work-feeding mechanism operated in synchronism with the vibratory frame in which said needle-bar is carried.

7. In a sewing machine the combination of an endwise reciprocatory needle-bar; a frame carrying said needle-bar and adapted to be vibrated in the line of feed; a needle secured to said needle-bar; a two-motion chain-stitch looper movable in a vertical plane and cooperating with said needle in the formation of stitches; a loop-spreader movable in a fixed path arranged transversely to the plane of movement of the looper for engaging the looper-thread and positioning the same so that the needle will pass into the looper-thread loop; and work-feeding mechanism operated in synchronism with the vibratory frame in which said needle-bar is carried.

8. In a sewing machine the combination of an endwise reciprocatory needle-bar; a frame carrying said needle-bar and adapted to be vibrated in the line of feed; a needle secured to said needle-bar; a two-motion chain-stitch looper movable in a vertical plane and cooperating with said needle in the formation of stitches; a loop-spreader movable in a fixed path arranged transversely to the plane of movement of the looper for engaging the looper-thread and positioning the same so that the needle will pass into the looper-thread loop; work-feeding mechanism including means for engaging the work upon opposite sides thereof; and means for operating said work-feeding mechanism in synchronism with the vibratory frame in which said needle-bar is carried.

9. In a sewing machine the combination of an endwise reciprocatory needle-bar; a frame carrying said needle-bar and adapted to be vibrated in the line of feed; a needle secured to said needle-bar; a thread enchain looper cooper-

ating with said needle in the formation of stitches; a loop-spreader adapted to engage the looper-thread and position the same so that the needle will pass into the looper-thread loop; work-feeding mechanism including means for engaging the work upon opposite sides thereof; and means for operating said work-feeding mechanism in synchronism with the vibratory frame in which said needle-bar is carried.

10. In a sewing machine the combination of an endwise reciprocatory needle-bar; a frame carrying said needle-bar and adapted to be vibrated in the line of feed; means for vibrating said frame; a needle secured to said needle-bar; a two-motion chain-stitch looper cooperating with said needle in the formation of stitches; a lower four-motion feeding mechanism operable upon one side of the work; an upper four-motion feeding mechanism operable upon the opposite side of the work; and means for operating said lower and upper feeding mechanisms in synchronism with the vibratory frame in which said needle-bar is carried.

11. In a sewing machine the combination of an endwise reciprocatory needle-bar; a frame carrying said needle-bar and adapted to be vibrated in the line of feed; a needle secured to said needle-bar; a two-motion looper cooperating with said needle and adapted to oscillate in a plane parallel to the line of feed and in a direction opposed to the feed when entering the needle-thread loop; a loop-spreader movable in a fixed path arranged transversely to the plane of movement of the looper for engaging the looper-thread and positioning the same so that the needle will pass into the looper-thread loop; and work-feeding mechanism operated in synchronism with the vibratory frame in which said needle-bar is carried.

12. In a sewing machine the combination of a frame including a bracket-arm terminating in a head, and a work-support; a rotary shaft journaled in said bracket-arm; a second rotary shaft journaled in said work-support; an endwise reciprocatory needle-bar; a needle secured to said needle-bar; a frame carrying said needle-bar and mounted upon said bracket-arm head to be vibrated in the line of feed; means actuated by the rotary shaft in said bracket-arm for imparting vibrations to said needle-bar frame; a two-motion chain-stitch looper actuated by the rotary shaft in said work-support and movable in a vertical plane for cooperation with said needle in the formation of stitches; work-feeding mechanism actuated by at least one of said rotary shafts, and means for operating said work-feeding mechanism in synchronism with the vibratory frame in which said needle-bar is carried.

13. In a sewing machine the combination of a frame including a bracket-arm terminating in a head, and a work-support; a rotary shaft journaled in said bracket-arm; a second rotary shaft journaled in said work-support; an endwise reciprocatory needle-bar; a needle secured to said needle-bar; a frame carrying said needle-bar and mounted upon said bracket-arm head to be vibrated in the line of feed; means actuated by the rotary shaft in said bracket-arm for imparting vibrations to said needle-bar frame; a two-motion chain-stitch looper actuated by the rotary shaft in said work-support and movable in a vertical plane for cooperation with said needle in the formation of stitches; an upper feeding mechanism actuated by the rotary shaft in said bracket-arm and including a feed-bar mounted in the

vibratory frame carrying said needle-bar; and a lower feeding mechanism actuated by the rotary shaft in said work-support.

14. A sewing machine having in combination a frame including a work-support and a bracket-arm terminating in a head; work-feeding mechanism; means for actuating said work-feeding mechanism; stitch-forming instrumentalities including a thread-carrying reciprocatory needle and a complemental looper cooperating therewith and having a loop-seizing position and a loop-shedding position; and mechanism designed for actuating said looper so that it is given a rapid deceleration and acceleration between said loop-shedding and loop-seizing positions.

15. A sewing machine having in combination a frame including a work-support and a bracket-arm terminating in a head; work-feeding mechanism; means for actuating said work-feeding mechanism; stitch-forming instrumentalities including a thread-carrying reciprocatory needle and a complemental looper cooperating therewith and having a loop-seizing position and a loop-shedding position; and mechanism designed for actuating said looper so that for a major portion of the cycle between said loop-seizing position and said loop-shedding position the looper is given a substantially uniform deceleration and acceleration and between said loop-shedding position and said loop-seizing position the looper is given a relatively rapid deceleration and acceleration.

16. A sewing machine having in combination a frame including a work-support and a bracket-arm terminating in a head; work-feeding mechanism; means for actuating said work-feeding mechanism; a frame pivoted upon said head and adapted to be vibrated in the line of feed; a needle-bar journaled for endwise movement in said vibratory frame; complemental stitch-forming mechanism including a looper having a loop-seizing position and a loop-shedding position; and mechanism designed for actuating said looper so that it is given a rapid deceleration and acceleration between said loop-shedding and said loop-seizing positions.

17. A sewing machine having in combination a frame including a work-support and a bracket-arm terminating in a head; work-feeding mechanism; means for actuating said work-feeding mechanism; a frame pivoted upon said head and adapted to be vibrated in the line of feed; a needle-bar journaled for endwise movement in said vibratory frame; complemental stitch-forming mechanism including a looper movable in a vertical plane parallel to the line of feed and having a loop-seizing position and a loop-shedding position; and mechanism designed for actuating said looper so that it is given a rapid deceleration and acceleration between said loop-shedding and said loop-seizing positions.

18. A sewing machine having in combination a frame including a work-support and a bracket-arm terminating in a head; work-feeding mechanism; means for actuating said work-feeding mechanism; a frame pivoted upon said head and adapted to be vibrated in the line of feed; a needle-bar journaled for endwise movement in said vibratory frame; complemental stitch-forming mechanism including a two-motion looper adapted to oscillate in a plane parallel to the line of feed and in a direction opposed to the feed when entering the needle-thread loop and having a loop-seizing position and a loop-shedding position; and mechanism designed for actuating said

looper so that it is given a rapid deceleration and acceleration between said loop-shedding and said loop-seizing positions.

19. A sewing machine having in combination a frame including a work-support and a bracket-arm terminating in a head; work-feeding mechanism; means for actuating said work-feeding mechanism; stitch-forming instrumentalities including a thread-carrying needle and a complementary looper cooperating therewith and having a loop-seizing position and a loop-shedding position; and mechanism including a guide-rod and sleeve connection for actuating said looper so that it is given a rapid deceleration and acceleration between said loop-shedding and loop-seizing positions.

20. A sewing machine having in combination a frame including a work-support and a bracket-arm terminating in a head; work-feeding mechanism; means for actuating said work-feeding mechanism; stitch-forming instrumentalities including a thread-carrying needle and a complementary looper cooperating therewith and having a loop-seizing position and a loop-shedding position; and mechanism for imparting to the looper between said loop-shedding position and said loop-seizing position a relative rapid acceleration, said mechanism including a crank, an oscillatable looper-carrier, and a link-and-lever arrangement connecting said crank to said looper-carrier for transmitting a variable motion to said looper.

21. A sewing machine having in combination a frame including a work-support and a bracket-arm terminating in a head; work-feeding mechanism; means for actuating said work-feeding mechanism; stitch-forming instrumentalities including a thread-carrying needle and a complementary looper cooperating therewith and having a loop-seizing position and a loop-shedding position; and mechanism for imparting to the looper between said loop-shedding position and said loop-seizing position a relative rapid deceleration and acceleration, said mechanism including a crank, an oscillatable looper-carrier, a link-and-lever arrangement connecting said crank to said looper-carrier, and means for controlling one of the elements of said link-and-lever arrangement thereby to impart to the looper a predetermined variable motion.

22. A looper mechanism for sewing machines including a looper; a looper-carrier; a support upon which said carrier is mounted; an actuating shaft; a crank upon said shaft; a link-and-lever arrangement connecting said crank to said looper-carrier; and means for controlling the path of travel of one of the elements in said link-and-lever arrangement to impart to the looper a predetermined variable motion.

23. A looper mechanism for sewing machines including a looper; a looper-carrier; a support upon which said carrier is mounted; an actuating shaft; a crank upon said shaft; a link-and-lever arrangement connecting said crank to said

5 looper-carrier; and means including a control sleeve and guide-rod for controlling the path of travel of one of the elements in said link-and-lever arrangement to impart a predetermined variable motion to the looper.

24. A looper mechanism for sewing machines including a looper; a looper-carrier; a support upon which said carrier is mounted; an actuating shaft; a crank upon said shaft; a link-and-lever arrangement connecting said crank to said looper-carrier; a control sleeve supported by one of the links in said link-and-lever arrangement; and a guide-rod fulcrumed upon said looper-carrier support and adapted to be received in 10 said control sleeve.

25. A looper mechanism for sewing machines including a looper; a looper-carrier; a support upon which said carrier is mounted; an actuating shaft; a crank upon said shaft; a rock-lever 15 secured to said looper-carrier support; a link connected to said rock-lever; a second link connected at one end to said first link and at its other end to said crank upon said actuating shaft; a control sleeve supported by said second link; and a guide-rod fulcrumed upon said looper-carrier support and adapted to be received in 20 said control sleeve.

26. A looper mechanism for sewing machines including a looper; a looper-carrier; a support 25 upon which said carrier is mounted disposed so that said looper moves in a vertical plane; an actuating shaft; a crank upon said shaft; mechanism connecting said crank to said looper-carrier; means for controlling the path of travel 30 of one of the elements in said mechanism; and a spreader cooperating with said looper.

27. A looper mechanism for sewing machines including a looper; a looper-carrier; a support 35 upon which said carrier is mounted disposed so that said looper moves in a vertical plane parallel to the line of feed; an actuating shaft; a crank upon said shaft; mechanism connecting said crank to said looper-carrier; means for controlling the path of travel of one of the elements 40 in said mechanism; a spreader cooperating with said looper; and means for actuating said spreader in a path transversely to the vertical plane of movement of the looper.

28. A looper mechanism for sewing machines 45 comprising a looper; a looper-carrier; an oscillatable sleeve upon which said looper-carrier is mounted; an actuating shaft; a crank upon said actuating shaft; a support for said oscillatable sleeve; a rock-lever secured to said oscillatable sleeve; a link connected to said rock-lever; a second link connected at one end to said first link and at the other to said crank upon the actuating shaft; a guide-rod freely fulcrumed 50 upon said oscillatable sleeve; and a control sleeve supported upon said second link and adapted to receive said guide-rod.

FREDERICK F. ZEIER.
